CLARENCE D. PLATT, OF BRIDGEPORT, CONNECTICUT.

FLUSH ATTACHMENT PLUG-RECEPTACLE.

968,261.

Specification of Letters Patent. Patented Aug. 23, 1910.

Application filed April 25, 1910. Serial No. 557,557.

To all whom it may concern:

Be it known that I, CLARENCE D. PLATT, a citizen of the United States, residing at Bridgeport, county of Fairfield, State of Connecticut, have invented an Improvement in Flush Attachment Plug-Receiptacles, of which the following is a specification.

This invention relates to flush attachment plug receptacles and has for its general object to simplify and cheapen and to greatly improve their construction and mode of operation in use.

It is one of the objects of the invention to provide a receptacle of this general character in which the terminals instead of being rigidly secured in place as heretofore shall be unattached and loose, and while securely retained in operative position, shall be free to move within reasonable limits so that should the plug contact pins be bent out of parallel, engagement may still be effected with the terminals.

A further object of the invention is to provide the receptacle with contact bushings so constructed that whenever engagement is made between the plug contact pins and the terminals of the receptacle, perfect electrical contact is effected even if the contact pins are appreciably bent out of parallel.

A further object of the invention is to provide a construction that shall dispense with the usual terminal attaching screws in the bottom of the receptacle.

A further object of the invention is to provide a receptacle so constructed that a pair of line wires may be passed through the receptacle without cutting the wires or tapping into a main.

With these and other objects in view the invention consists in certain constructions and in certain parts, improvements and combinations which will be hereinafter described and then specifically pointed out in the claims hereunto appended.

In the accompanying drawing forming a part of this specification, Figure 1 is a front elevation of my novel receptacle with a plug in engagement therewith, the face plate and plug being partly broken away; Fig. 2 a side elevation partly in vertical section; Fig. 3 an end elevation partly in section, the plug being detached; Fig. 4 a perspective of the insulating top block detached; Fig. 5 a per-

spective of the base detached; and Fig. 6 is 55 a perspective of one of the terminals detached.

10 denotes the box or casing, 11 an insulating base within the casing, 12 an insulating top block, 13 the cover plate, 14 60 the terminals as a whole, 15 electrical conductors, 16 a plug and 17 the contact pins. The base is provided with a recess 18 at the bottom of which are sockets 19 which receive the terminals and at the ends of the 65 base are outwardly extending lugs 20. Each terminal comprises a plate 21 bent to the form of steps, the lower step indicated specifically by 21^a resting in one of the sockets 19. This step has rigidly secured 70 thereto a contact bushing 22 which is adapted to receive one of the contact pins. Each pin is provided with a circumferential groove 23 which is engaged by a projection 24 on a spring 25 which is formed by making cuts 26 in the bushing. The action of the spring is to force the pin against the wall of the bushing so as to effect practically a perfect contact as a large portion of each pin is held in engagement with the corresponding bushing. 27 denotes a binding screw which engages the upper step of plate 21 which is specifically indicated by 21^b. The angle of this upper step which is indicated by 28 engages a shoulder 29 in the 75 base. It will be understood from Fig. 5 in connection with Fig. 1 that these binding screws are diagonally opposite to each other. The insulating top block is so shaped as to loosely retain the terminals in place and to 80 fill recess 18 in the base. It is provided in its underside with holes 30 which receive the contact bushings loosely and in alinement therewith, with guide holes 31 through which the contact pins pass, these guide holes terminating in circular flanges 32 which extend through holes 33 in the cover plate. On opposite sides of the top block are recesses 34 which receive the upper steps of the terminals and the binding screws. The top 85 block is secured to the base by screws 35 which pass upward through lugs 20 and through the ends of the top block and also secure ears 36 to the top block. The top block and base are secured in the casing by 90 screws 37 which pass through ears and engage the ends of the casing, and the cover plate is secured in place by means of 95 100 105

screws 38 which engage the ears. The special objects of this construction of the base and top plate are to leave the terminals unattached and free to move within reasonable limits so that they may be engaged by the contact pins and perfect electrical contact made even though the pins should be bent appreciably out of parallel and furthermore to avoid the necessity for terminal attaching screws in the bottom of the base. It will of course be understood that the use of these attaching screws is necessarily objectionable. They add to the cost of manufacture and require that the base be perforated, the holes being ordinarily filled, after assembling, with wax, which will melt at a relatively low temperature and leave the screws exposed. The electric conductors, which may be the line wires, enter the casing through holes 39, pass between the casing, the ends of the base and lugs 20 and then pass over the base and top block and downward and out at the other end of the base. 40 denotes longitudinal grooves or channels which are formed partly in the base and partly in the top block to receive the conductors, so that they will be effectually insulated by walls of insulating material. By providing the stepped terminals and placing the binding screws on the upper step thereof I avoid the necessity of tapping into the mains or line wires for each receptacle and simply pass the line wires themselves through the receptacles, each line wire being passed through one of the grooves 40 in the base and top block and a portion thereof being skinned, as at 41 in Fig. 1, and passed under a binding screw in close engagement therewith. I preferably use upon my novel receptacle the form of insulated cover plate described and claimed in my former Letters Patent No. 948,707, dated Feb. 8, 1910, although that is not essential, as with my present construction there need be no cutting of the line wires and consequently no free ends of wire, the line wires being wholly within the grooves or channels in the base and top block and out of contact with any metallic parts.

50 The plug, indicated as a whole by 16, comprises a block 42 of insulating material having a hole 43 through which the electrical conductor passes and a recess 44 in which the terminals 45 carrying binding screws 46 are secured. The contact pins are provided with reduced ends which pass through holes in the terminals leaving shoulders 47 which engage the terminals, the ends of the pins being molded rigidly in the plug. This construction enables me to dispense with the usual terminal attaching screws and leaves the surface of the plug clear for marking purposes.

48 denotes an insulating cover plate for the plug which is preferably made of fiber

and is secured to the underside of the plug covering the recess and effectually insulating the terminals and binding screws.

Having thus described my invention, I claim:

1. A receptacle of the character described comprising a base having a recess, loose terminals in said recess and a top block by which the terminals are retained in place. 70

2. A receptacle of the character described comprising a base having a recess, loose terminals in said recess each comprising a stepped plate, a contact bushing and a binding screw and a top block by which the terminals are retained in place. 75

3. A receptacle of the character described comprising a base having a recess, loose terminals in said recess each comprising a plate having upper and lower steps, a contact bushing secured to the lower step, and a binding screw engaging the upper step, and a top block by which the terminals are retained in place. 80

4. A receptacle of the character described comprising a base having a recess with sockets in its bottom and shoulders, loose terminals seated in the sockets, each comprising a lower step having a contact bushing secured thereto and an upper step having an angle engaging the shoulder and a binding screw and a top block having recesses which receive the upper ends of the terminals and the binding screws and which retains the terminals in place. 90

5. A receptacle of the character described comprising a base having a recess, loose terminals in said recess each comprising a plate having upper and lower steps, a contact bushing secured to the lower step and a binding screw engaging the upper step, 105 and a top block having holes which receive the contact bushings and guide holes for contact pins in alignment therewith.

6. A receptacle of the character described comprising a casing, a base secured thereto, terminals and binding screws in the base and a top block, said base and top block being provided with grooves in alignment with the binding screws through which the line wires may pass without cutting. 110

7. A receptacle of the character described comprising a casing having holes for conductors, a base having lugs at its ends by which it is secured to the casing, terminals and binding screws in the base, and a top block, said base and top block being provided with longitudinal grooves in alignment with the binding screws and line wires which pass between the casing and the base, along the grooves and in engagement with the binding screws and out at the other end of the casing. 120

8. A receptacle of the character described comprising a base having a recess, loose terminals seated therein, each comprising a 130

plate having a lower step with a contact bushing secured thereto, and an upper step with a binding screw and a top block covering the recess in the base and having recesses to receive the upper steps of the terminals and the binding screws.

9. A receptacle of the character described comprising a base having a recess, loose terminals seated therein, each comprising a plate having a lower step with a contact bushing secured thereto, and an upper step with a binding screw and a top block covering the recess in the base and having recesses to receive the upper steps of the terminals and the binding screws, said base and top block having grooves in alinement with the binding screws which are adapted to receive line wires without cutting.

10. A receptacle of the character described comprising a base having a recess, loose terminals seated therein, each comprising a plate having a lower step with a contact bushing secured thereto, and an upper step with a binding screw and a top block covering the recess in the base and having holes which receive the contact bushings and guide holes for contact pins in alinement therewith.

11. The combination with a receptacle comprising a base having a recess, loose terminals therein, each comprising a stepped plate, a contact bushing and a binding screw and a top block having holes to receive the contact bushings loosely and guide holes in alinement therewith, of a plug having contact pins adapted to pass through the guide holes and engage the bushings.

12. The combination with a receptacle comprising a base having a recess, loose terminals therein each comprising a lower step

carrying a contact bushing and an upper step carrying a binding screw and a top block having holes to receive the contact bushings loosely, guide holes in alinement therewith and recesses to receive the upper steps and binding screws, of a plug having contact pins adapted to pass through the guide holes and engage the bushings.

13. The combination with a base having a recess, loose terminals therein each comprising a plate having upper and lower steps, a contact bushing secured to the lower step and provided with a spring, and a binding screw engaging the upper step and a top block having holes to receive the bushings loosely and guide holes in alinement therewith, of a plug having contact pins which are adapted to pass through the guide holes and into the bushings and be held in engagement therewith by the springs.

14. The combination with a base having a recess, loose terminals therein each comprising a plate having upper and lower steps, a contact bushing secured to the lower step and provided with a spring having an engaging projection and a binding screw engaging the upper step and a top block having holes to receive the bushings loosely and guide holes in alinement therewith, of a plug having contact pins which are adapted to pass through the guide holes and into the bushings and are provided with grooves which are engaged by the projections on the spring.

In testimony whereof I affix my signature in presence of two witnesses.

CLARENCE D. PLATT.
